UNITED STATES PATENT OFFICE.

WILLIAM M. MYERS AND AUGUSTUS SMITH, OF COSBY, MISSOURI.

CLIP FOR EVENERS.

SPECIFICATION forming part of Letters Patent No. 366,862, dated July 19, 1887.

Application filed April 9, 1887. Serial No. 234,296. (No model.)

To all whom it may concern:

Be it known that we, WILLIAM M. MYERS and AUGUSTUS SMITH, citizens of the United States, residing at Cosby in the State of Missouri, have invented certain new and useful Improvements in Clips for Eveners; and we do declare the following to be a full, clear, and exact description of the invention, such as will enable others skilled in the art to which it appertains to make and use the same.

Our invention relates to whiffletree-irons; and it consists in the construction and novel arrangement hereinafter specified and claimed.

In the accompanying drawings, Figure 1 represents a side elevation of a portion of a doubletree and a whiffletree, showing our improvements applied. Fig. 2 is a plan view of the same, and Fig. 3 is a longitudinal vertical sectional view. Fig. 4 is a vertical cross-section view. Fig. 5 is a horizontal section taken beneath the whiffletree with the bolt removed, and Fig. 6 is an inverted plan view of a portion of the whiffletree with the spring-washer E applied.

The letter A of the drawings represents a casting, preferably of malleable iron, which is provided with a transverse rectangular opening, c, to receive a doubletree, and a vertical aperture, d, intersecting the said transverse opening c, to receive the king-bolt. Surrounding the upper end of the vertical aperture is a boss, e, to receive a spring-washer, as shown.

It will be observed that all of these parts are formed entire, and the objectionable necessity of employing bolts and nuts for uniting the parts thereby dispensed with. This casting is also provided with a clevis, f.

The letter B represents a doubletree arranged in the opening c, and C represents a single whiffletree.

The letter D represents a spring-washer, attached in any suitable manner to the singletree between its top portion and the curved arm of the main casting above the opening d.

The letter E represents a spring-washer attached to the bottom portion of the singletree, and is interposed between said singletree and that part of the casting A which forms the upper wall of opening c. The lower side of the last-mentioned washer is provided with a circular recess, g, adapted to fit upon and clasp the boss e of the main casting.

For the purpose of holding the double-

tree securely within the opening c, we form 55 upon the upper wall of said opening an extension or lug on each side, as shown at h on the drawings. Screw-holes n are made near the ends of said extensions, through which screws are passed into the doubletree to 60 hold it in position and prevent lateral movement. One of said extensions and screws are usually found ample for the purpose mentioned; but we prefer to use two for greater safety.

The washers connected with the singletree are preferably made of spring-steel; but any other substance of an elastic character may be employed for the purpose; and even if said washers have no spring action whatever they 70 are found to serve quite well for the purpose desired.

With the several parts constructed as above mentioned, I pass a strong bolt (marked W) through the head of the arm above the upper opening down through the singletree and its washers, the walls of the lower opening, and the doubletree. The lower end of the bolt W being provided with a screw-thread, we arrange then a suitable nut, and the work is 80 completed.

In using our invention it is found that the wearing of oblong or angular holes in the doubletree, by the function that usually accompanies the action of a singletree, attaching 85 bolts is effectually prevented, and increased permanence and durability are secured.

In case the wear of the singletree and its washers renders the parts too loose, they are easily tightened by turning the nut on the lower 90 end of the bolt W.

We claim as our invention and desire to secure by Letters Patent—

The casting A, having the clevis f, the transverse rectangular aperture c, the upper 95 forwardly-directed curved arm perforated at its outer end and all formed entire, in combination with a doubletree passing through the rectangular aperture, a singletree beneath the curved arm, the spring-washers, and the bolt 100 passing vertically through all of the parts to unite the same, substantially as specified.

In testimony whereof we affix our signatures in presence of two witnesses.

WILLIAM M. MYERS. 105

Witnesses: AUGUSTUS SMITH.

GEO. W. HINTON,
E. L. BOWER.
